RHEOSTAT

Frank W. McDonell, Fairlawn, and Victor L. Osgood, West Orange, N. J., assignors to Hardwick, Hindle, Inc., Newark, N. J.

Application April 12, 1934, Serial No. 720,164

8 Claims. (Cl. 201—56)

This invention relates to the design of a rheostat and has for one of its objects the design of a rheostat of the type suitable for mounting on mounting plates or panel boards which, by way of illustration but not of limitation, may be found in radio receiving sets.

In rheostats of the type heretofore referred to it has been the practice to use the control arm either directly or indirectly as a conductor of current from one side of the circuit to the resistance winding element. In these prior art designs much difficulty is encountered in making electrical connection through the rotating shaft and arm to the resistance winding. In certain cases flexible cables are used in shunt to the arm, and springs are utilized to force the shaft endwise, so as to cause the arm or an auxiliary member carried directly thereby to firmly engage the resistance winding.

It is the principal object of our invention to provide a rheostat in which the difficulties of carrying the current through the shaft and rotating arm are entirely avoided by the complete elimination of the shaft and contact-carrying arm from the rheostat circuit.

Another object of our invention is to provide a new form of contact device which is self-aligning on the resistance winding, and a cooperating contact member, whereby good contact will always be insured even though the outer peripheries of the convolutions of the winding are not in exactly the same plane, or in the plane of an associated contact member which cooperates with the contact device carried by the movable arm.

Another object of our invention is to provide a contact device to be carried by the movable arm in such a manner that it may be quickly changed if desired.

Another object of our invention is to provide an improved means for mounting the rheostat on a mounting plate or panel.

Other and further objects will appear from the description taken in connection with the drawing wherein:

Figure 1 is a view of the contact end of one form of our invention.

Figure 2 is a side elevation of the rheostat shown in Figure 1.

Figure 3 is a vertical section through the rheostat shown in Figures 1 and 2.

Figure 4 is a perspective view, on a somewhat enlarged scale from the previous figures, of the contact device carried by the movable arm of the rheostat.

Figure 5 is a perspective view of the holder

forming part of the contact device shown in Figure 4.

Figure 6 is a perspective view of one of the contact members per se.

Figure 7 is a perspective view of the holder and 5 the end of the arm carrying the holder.

Figure 8 is a view similar to Figure 1 but of a smaller and somewhat modified form of our invention.

Figure 9 is a vertical sectional view through 10 Figure 8.

Figure 10 is a perspective view of the holder and contact members used in the device shown in Figures 8 and 9.

Figure 11 is a side view of one of the contact 15 members shown in Figure 10.

Figure 12 is a view of the holder carrying the contact members of Figure 11.

Figure 13 is a fragmentary sectional view of a rheostat support member such as shown in Figure 8, but showing a modified form of stationary contact member for cooperation with the movable contact.

Figure 14 is a plan view of the auxiliary contact member shown in Figure 13.

Figure 15 is a fragmentary view of the method of mounting the rheostat to a mounting plate or support panel. This view is very similar to the part shown in Figure 9.

Figure 16 is a perspective view of the locking 30 mounting member shown in Figures 9 and 15.

Figure 17 is a fragmentary view of the mounting panel to cooperate with the locking member shown in Figure 16.

Figure 18 illustrates a modified form of stop 35 means for the rheostat contact arm.

Figure 19 is a sectional view through the contact arm end of a still further modified form of rheostat.

In the various views of the drawing, 1 is a support member having a base portion 2 and a central hub portion 3 with a sector 4 extending therefrom to the periphery of the base portion 2. The parts just described are of high heat-resisting material, preferably of the ceramic type.

Supported on the base portion 2, is a circular form 5 of high heat-resisting material, preferably of a ceramic type. As shown in Figure 1, the form 5 terminates on opposite sides of the sector 4 and carries a resistance winding of suitable material, the ends of the winding being provided with terminals 6 and 7. The winding is entirely covered, except for a brush track surface 8, with a vitreous enamel 9 which also acts to cement or anchor the winding unit, comprising 55

ing the wire and form 5, to the base portion 2 of the support member 1. The method of preparing the resistance unit per se is preferably as shown and described in Crouse Patent 1,880,239, issued October 4, 1932, and need not be further described herein.

The hub 3 of the support member carries an annular contact member 10 which is arranged concentrically and spaced a distance within the inner periphery of the circular form 5 carrying the winding. The contact member 10 is fastened to the upper surface of the hub 3 in any satisfactory manner as by a plurality of downwardly bent lugs 11 which pass into small openings in the end of the hub which are preferably filled with cement and which, on setting, anchor the member 10 securely in place. The member 10 is provided with a terminal 12 for making electrical contact thereto. Preferably the terminal 12, in extending radially from the contact member 10, is positioned between a pair of positioning lugs 13 which project slightly upward from the upper surface of the sector 4, thereby assisting in holding the member 10 securely in operating position.

The hub 3 has a central hole therethrough and in this hole is positioned a sleeve 14 having a collar 15 at one end, engaging a shoulder adjacent one end of the hole. The other end of the sleeve 14 is threaded at 16 and provided with a nut 17 to securely lock the sleeve in position in the hub. An operating shaft 18 is positioned in the sleeve 14 by means of a pin 19 carried by the shaft 18 adjacent the collar 15, and a lock ring 20 carried in a groove in the shaft 18 adjacent the threaded end 16 of the sleeve 14. The pin 19 also acts as a stop for the rotary movement of the shaft by engaging the inner projecting parts 21 of the sector 4.

40 The end of the shaft 18 adjacent the annular contact member 10, carries an arm 22 which is preferably of resilient metal and which arm is securely attached to a collar 23 which is preferably fastened to the shaft 18 by one or more set screws 24, two being illustrated in Figure 1. The arm 22 has an orifice at its free end and this orifice, in the form of rheostat shown in Figures 1 to 7, is in the shape of an elongated slot 25. The slot 25 is adapted to receive a similarly 50 shaped projection 26 extending from one side of a holder 27 comprising part of a contact device. However, the holder 27 is made of strong insulating and preferably heat-resisting material of a ceramic nature, and has on the side, as shown 55 in Figure 5, an arcuately formed seat 28 adapted to receive a curved lug 29 on one face of a contact device 30 which is preferably of a metal of good conducting quality, such as copper or a composition thereof.

60 As clearly shown in Figures 4 and 5, two members 30 are utilized and are held in place by the side members 31 and 32. It will be noted that the members 30 are loosely and freely carried in the holder 27 which itself is more or less flexibly carried on the flexible arm 22, and when the parts are assembled as shown in Figure 3, the contact devices 30 extend or bridge across the annular contact member 10 to the track surface 8 of the winding, it being understood that the 65 track surface 8 and the surface of the annular contact member 10 are substantially in the same plane. However, by reason of the construction described, if one of the convolutions of the winding should extend slightly above its next adjacent one, the member 30 being free to oscillate

in the holder 27 as described, will readily move as indicated in Figure 4 to take up the necessary alignment, whereby a good contact is insured at both ends of the members 30. The tension of the contacts between the winding and the member 10 is initially obtained by adjusting the collar 23 carrying the arm 22 on the shaft 18, by reason of the set screw 24.

5 In the form of rheostat shown in Figure 8, the construction is very similar to that already described, except that in this form the support member 1 is provided with an annular groove 36 within the body of the support 1, and this annular groove carries the form 5 and the winding, being anchored in the groove by the vitreous 15 enamel 9. In addition, the arm 22 is riveted to the end of the shaft 18 and the pressure on the contact device to be described is obtained by giving the arm 22 the proper "set", it being understood that the length of the shaft is such 20 as to bring the arm 22 in substantially operative position after it has been riveted to the end of the shaft.

25 In this form of rheostat, the contact device is somewhat different from that previously described, in that it comprises a circular holder 33 having an extension with a flat side 34 to fit a correspondingly shaped hole in the arm 22. Furthermore, the arcuately formed seat 28 is of a little different shape than that shown in Figure 30 5, and likewise the contact members 35 are shaped differently from those shown in Figure 6, but they operate in the holder 33 to produce the same result as the construction shown in Figures 4, 5, and 6.

35 In Figure 13, the support member 1, which is substantially the same as that shown in Figure 8, carries a contact member 37 constructed of a flat strip of metal bent around as shown in Figure 14 and fitted edgewise into an annular 40 slot provided in the support member 1, being anchored therein by suitable cement. In addition, the stop member may consist of a U-shaped member 45 set in the support 1 in the manner as illustrated in Figure 18, and in which the edge 45 of the holder 33 will strike either one of the arms of the U-shaped member 45.

An important feature of our invention is the method of mounting the rheostat on the panel or supporting plate, and we have provided means by 50 which the rheostat may have a single hole mounting; that is to say, the same hole which is drilled to receive the shaft also serves for mounting the rheostat on the panel. In such a mounting it is quite essential that the operation of 55 the knob carried on the end of the shaft 18 will not turn the rheostat, and to absolutely prevent this taking place, we have provided a locking disc 38 adapted to fit over the threaded portion 16 of the sleeve 14, being positioned against 60 the sleeve locking nut 17. The disc 38 has a lug 39 extending into a recess 40 in the support member 1.

65 In addition, the disc 38 has two fingers or projections 41 that are adapted to enter holes 42 in the mounting panel 43, so that when the panel locking nut 44 is screwed up on the threaded end 16 of the sleeve 14, the rheostat is locked securely in position on the panel through the locking disc 38.

70 From the constructions so far described, it will be seen that the arm 22 carries no current and forms no part of the electrical circuit through the rheostat, the current coming in, for example, by way of the terminal 12 and its con- 75

tact ring 13, through the members 36 or 35, to the winding and through the terminals 6 and/or 7. Furthermore, it will be observed that no springs are required in connection with the shaft 18 to put tension on the contact members.

Figure 19 shows a sectional view through one end of the rheostat in which the resistor is carried in the support member 1 and connections made thereto as shown in Figure 8. Likewise, the device is provided with an annular ring member 37 substantially as shown in Figure 13. However, the shaft 18 carries an insulator 46 which is fastened thereto in any satisfactory manner as by pin 47. The insulator 46 carries a circular contact member 48 which has a depression 49 in continuous contact with the annular member 37.

Preferably diametrically opposite to the depressed portion 49 the annular member is provided with a projection or finger 50 which is in continuous engagement with the track surface 8 on the resistor. Preferably the circular contact member has a pair of arcuate slots 51 spaced a distance from the insulator for the purpose of promoting the flexibility of the contact member.

It will thus be seen in this particular form that while the contact arm itself carries current, no current passes through the shaft or any extraneous spring.

From what has been said, it will be understood that certain of the details for carrying our invention into practice may be varied to some extent, but such variations should come within the scope of the appended claims.

What we claim is:

1. In a rheostat, a support member, a circular form of heat-resisting material having a winding thereon and means for fastening said form and winding to the support member, a part of the surface of said winding being exposed to form a brush track, an annular contact member concentrically carried on said support member adjacent said winding, an arm concentrically mounted for rotation with respect to said form and winding, an insulator carried at the free end of said arm, and a current-carrying device carried by said insulator so as to simultaneously engage both the said annular contact member and said brush track on the winding, said rheostat being further characterized in that said arm insulator has a projection on one side for engagement with said arm, and an arcuately formed seat on the opposite side, and at least one contact device oscillatably carried in said seat.

2. In a rheostat, a support member, a circular form of heat-resisting material having a winding thereon and means for fastening said form and winding to the support member, a part of the surface of said winding being exposed to form a brush track, an annular contact member concentrically carried on said support member adjacent said winding, an arm concentrically mounted for rotation with respect to said form and winding, an insulator carried at the free end of said arm, and a current-carrying device carried by said insulator so as to simultaneously engage both the said annular contact member and said brush track on the winding, said rheostat being further characterized in that said arm insulator has a projection on one side for engagement with said arm, and an arcuately formed seat on the opposite side, and a plurality of contact devices carried in said seat so they can have local independent oscillating movement.

3. In a rheostat, a support member, a circular form of heat-resisting material having a winding thereon and means for fastening said form and winding to the support member, a part of the surface of said winding being exposed to form a brush track, an annular contact member concentrically carried on said support member adjacent said winding, an arm concentrically mounted for rotation with respect to said form and winding, an insulator carried at the free end of said arm, and a current-carrying device carried by said insulator so as to simultaneously engage both the said annular contact member and said brush track on the winding, said rheostat being further characterized in that said arm insulator has a projection on one side for engagement with said arm, and a seat on the opposite side for at least one contact device, the seat and contact device having cooperative surfaces whereby the contact device may oscillate so it can readily follow any irregularities in the winding track.

4. In a rheostat, a support member of heat-resisting insulating material, a circular core of heat-resisting material having a winding thereon, said winding and core being covered, except for one exposed side, with a vitreous enamel which also acts to anchor the winding and core to said support member, an annular contact ring concentrically mounted on said support member within the inner periphery of said winding and substantially on the same plane as the exposed side of said winding, a metallic arm concentrically mounted for rotation with respect to said winding, a contact holder of insulating material on the end of said arm and formed to provide a seat for a contact shoe, and at least one contact shoe loosely and oscillatably nested in said seat of said holder to maintain a continuous engagement with said exposed part of the winding and said annular contact ring.

5. In a rheostat having a frame, a threaded bearing sleeve having a nut to clamp the sleeve to the frame, an operating shaft extending through the sleeve, means for mounting the rheostat on a panel, comprising a hole through the panel for said shaft and sleeve, a plate initially loose and removable on the sleeve and having a finger adapted to enter a recess in the rheostat frame, at least one projection extending from the plate in the opposite direction to said finger into the panel, and a nut on the sleeve on one side of the panel to draw the rheostat and plate against the opposite side of the panel.

6. In a rheostat having a threaded bearing sleeve and an operating shaft extending through the sleeve, means, for mounting the rheostat on a support, comprising a hole through the support for the shaft and sleeve, a plate removably carried on the threaded part of the sleeve between the rheostat and said support, said plate having means to engage a part of the rheostat, and further means for engaging said support, and means carried on the sleeve to clamp said rheostat and plate securely against said support.

7. In a rheostat having a single hole threaded sleeve mounting to a support, means independent of the rheostat per se, for preventing said rheostat from turning on the support, comprising a separable plate located concentrically on the threaded part of the sleeve and between the rheostat and support, said plate having means to engage a part of the rheostat, and further means for engaging said support, and means car-

ried on the sleeve to clamp said rheostat and plate securely against said support.

8. In a rheostat, a support member of insulating material, a circular core having a winding thereon with means for fastening the core to the support, at least the core being of high heat-resisting material, the winding and core being covered, except for the top free edge of the winding, with a vitreous enamel coating, an annular contact ring carried on said support member concentrically with the winding and substantially on the same plane as the exposed top edge of the

winding, an arm concentrically mounted for rotation with respect to the winding and carrying contact-holding means, at least one of which is of insulating material, said holding means being formed to provide a seat for a contact shoe, and at least one contact shoe loosely and oscillatably nested in said seat of said holding means to maintain a continuous engagement with said exposed part of the winding and said annular contact ring.
